UNITED STATES PATENT OFFICE

JOHN S. TRAVIS, OF LONG ISLAND CITY, NEW YORK, ASSIGNOR TO BIGELOW SANFORD
CARPET CO., INC., A CORPORATION OF MASSACHUSETTS

DESIGN FOR A CARPET

Application filed November 12, 1932. Serial No. 45,943. Term of patent 7 years.

To all whom it may concern:

Be it known that I, JOHN S. TRAVIS, a citizen of the United States, residing at Long Island City, in the county of Queens and State of New York, have invented a new, original, and ornamental Design for a Carpet, of which the following is a specification, reference being had to the accompanying drawing, forming part thereof.

The drawing illustrates a portion of a carpet showing my design.

The dot and dash lines define the unit of the design. The lower right hand vertical edge of the unit designated "A", is repeated at the upper left hand vertical edge of the unit designated "B", while the upper right hand vertical edge of the unit designated "C", is repeated at the lower left hand vertical edge designated "D".

I claim:

The ornamental design for a carpet substantially as shown and described.

JOHN S. TRAVIS.
